UNITED STATES PATENT OFFICE.

JOHN N. REYNOLDS, OF GREENWICH, CONNECTICUT, ASSIGNOR, BY MESNE ASSIGNMENTS, TO WESTERN ELECTRIC COMPANY, INCORPORATED, A CORPORATION OF NEW YORK.

TERMINAL BANK.

1,257,394.

Specification of Letters Patent. Patented Feb. 26, 1918.

Application filed September 17, 1915. Serial No. 51,259.

To all whom it may concern:

Be it known that I, JOHN NEWBERRY REYNOLDS, a citizen of the United States, residing at Greenwich, in the county of 5 Fairfield and State of Connecticut, have invented certain new and useful Improvements in Terminal Banks, of which the following is a full, clear, concise, and exact description.

10 This invention relates to contact banks for switches of the panel type.

One of the objects of the invention is the provision of a contact bank in which the projecting switch contacts are formed as 15 integral rebent portions of line terminal wires or strips.

Another object of the invention is to so twist or cross the wires or strips forming the terminals of a group of conductors individual to a line that inductive action will 20 be prevented and crosstalk will thus be avoided.

A further feature of the invention is the provision of a panel bank having the above 25 advantages in which the contacts will be arranged on opposite sides thereof.

Referring to the drawing, Figure 1 is a plan view of a section of the panel bank of the above described character; Fig. 2 30 shows a modification of the bank shown in Fig. 1; Fig. 3 is a similar view of another modification; Fig. 4 is a similar view of still another modification; and Fig. 5 is a face view showing the arrangement of the 35 contacts of the modification shown in Fig. 4.

Referring first to Fig. 1, it will be noted that all the contacts of the several sets shown thereon are formed as projecting or rebent portions of two pairs of terminal 40 wires 1, 2 and 3, 4. The contacts 1', 1'', 1''', 1'', etc., are all formed as projecting or rebent portions of the wire 1, and the contacts 2', 2'', etc., are formed as similar integral portions of the wire 2. Likewise the 45 contacts 3', 4', etc., are formed from the strips 3 and 4 respectively.

The contact bank shown in Fig. 1 is designed to be used with a structure such as that shown in Patent 1,172,585, issued February 22, 1916, to Henry F. Dobbin, and the series or rows of contact sets are so arranged that the same switch may traverse either one or the other of a pair of adjacent

contact rows. The strips 1 and 2 are the terminals of the two conductors of one 55 telephone line, while the strips 3 and 4 are the terminals of the conductors of a different line. The set of terminals 1' and 2' would be in a companion row or series with the set of terminals 3' and 4', and would 60 be positioned at the same relative position in the series.

The twisted arrangement of the terminal wires, as herein shown, effectually prevents all crosstalk. It is, of course, to be understood that the wires or strips are coated with an insulating substance, such as enamel or shellac, before they are formed into a terminal set. The coating may afterward be removed from the projecting or contact 70 portions in any desired manner.

In Fig. 2, a bank is shown in which there are three contacts in a set and consequently three terminal strips or wires 5, 6 and 7, the contacts 5', 5'' and 5''' being 75 formed as rebent or projecting portions of the wire 5, while contacts 6', 7', etc., are formed as rebent portions of the wires 6 and 7 respectively.

In Fig. 3 is shown a portion of a bank 80 similar to that shown in Fig. 1 with the exception that the rows of contact sets are separated from each other and do not occur in pairs. In this bank, contacts 8', 8'', etc., are formed from the wire 8, while the 85 contacts 9', 9'', etc., are formed from the wire 9. In Fig. 4 is shown a bank designed for use with a switch such as shown in Patent 1,122,642, issued December 29, 1914, to John N. Reynolds. In this modification the contacts 10', 11' and 12', etc., are formed from the wires 10, 11 and 12 respectively. It is thought that this figure taken with Fig. 5 is self-explanatory and need not be further described.

In the completed bank the individual groups or sets of terminal strips will be insulatively mounted one above the other in a bank with the similar terminals of the several groups arranged in rows. This is 100 preferably accomplished by inserting the strips in a mold with only the contact portions projecting therefrom, and then casting or pouring the molten insulating material about the body portions of the strips. 105 If desired, however, the bank may be built

2
up in a manner similar to that disclosed in Patent 1,127,741 issued February 9, 1915, to Amos F. Dixon.

What is claimed is:

- 5 1. A terminal bank for switches comprising a plurality of longitudinally extending separated conductors, each conductor being provided between its ends with a plurality of contact surfaces projecting therefrom, and a mounting strip in which said conductors are secured in non-inductive relation to each other.
- 10 2. A terminal bank for switches comprising a plurality of longitudinally extending conductors, each conductor being provided between its ends with a plurality of integrally formed contact surfaces projecting therefrom, and a mounting strip in which said conductors are secured in non-inductive relation to each other with the contact surfaces thereof projecting from said strip.
- 15 3. A terminal bank for switches comprising

ing a mounting strip, and a plurality of longitudinally extending bare conductors embedded in said strip in a non-inductive 25 and non-conductive relation to each other, each of said conductors being provided with a plurality of contact surfaces between its ends projecting from said strip.

4. In a terminal bank, the combination 30 of sets of twisted conductors embedded in a solid mass of insulating material, and sets of multiple contacts integral with said conductors.

5. In a terminal bank, a pair of wires 35 having integral projecting contact portions, said wires being transposed and embedded in an insulating compound so that the contact portions project from the face 40 of the bank.

In witness whereof, I hereunto subscribe my name this 16th day of September A. D., 1915.

JOHN N. REYNOLDS.
